AIR LOCK COAL SCALE

Arthur J. Stock, Cleveland, Ohio

Application October 31, 1951, Serial No. 254,130

9 Claims. (Cl. 249—38)

1

This invention relates to a bulk material scale apparatus for operation with a system under pressure and more particularly to a coal scale for use with either pressure or vacuum furnaces or burners.

In the handling of bulk material wherein it is transported from a starting point at atmospheric pressure through a weighing operation to a remote point under pressure, a stoppage of the bulk material will generally result in gases or vapors being blown back through the system from the remote point under pressure. These gases generally contain dust or other obnoxious impurities and usually gain access to the atmosphere at the starting point thereby polluting the surrounding area and resulting in the discomfiture of persons in the immediate vicinity. Similar difficulties are encountered when the remote point is under vacuum where it is desirable to prevent the entry of air at the starting point.

While this problem is present in all types of bulk material systems of this nature, nevertheless, it has particular reference to coal handling installations feeding pressure or vacuum furnaces or burners where there is an added danger of fire. A normal coal installation of this type stores the coal in a bunker for transportation through a feeding system including conveyors, a scale apparatus, chutes, downspouts and a feeder, to a pressure or vacuum furnace.

In order to burn coal in very large boiler furnaces, it has been the custom in many installations to first pulverize the coal and then blow the powdered coal into the furnace where it burns as a gas. Equipment necessary to carry out the foregoing operation consists of a pulverizer, a feeder for that pulverizer, and a fan which picks up air and pulverized coal and forces that combustible mixture into the boiler furnace.

One arrangement of equipment places the fan between the pulverizer and the boiler furnace. If the pressure within the boiler furnace is slightly negative, as it usually is, then the interior of the pulverizer is under a small vacuum. Consequently, if the coal feed pipe between the coal feeder and the pulverizer were left open to the atmosphere, most of the combustion air would rush through this pipe. Therefore the feed pipe is made airtight by constantly having a solid head of crushed coal of several feet located therein to act as a reasonably good air seal between the atmosphere and the interior of the pulverizer, and thus only a small quantity of cold air leaks into the pulverizer.

With the arrangement as suggested above there

2

is some wear on the blades of the fan due to the erosion caused by the coal dust from the pulverizer moving over the fan blades. In order to reduce fan maintenance, some installations place the fan ahead of the pulverizer. This puts the pulverizer under positive pressure and also the pulverizer feeder. Here again, a column of coal several feet high ahead of the pulverizer feeder has been used as a seal to prevent loss of air into the atmosphere through the coal.

It is desired in many installations to preheat the combustion air. Hence it is necessary to reduce to a minimum the leakage through the feed pipe.

15 The above and foregoing remarks have been made in reference to a boiler furnace operating under a slight negative pressure by reason of the utilization therewith of an induced draft fan. However, the more recent tendency is to utilize 20 a forced draft fan. This means that the boiler furnace operates under a positive pressure, and as a result the pressure existing at the pulverizer feeder is several times as great as it was with installations employing an induced draft fan. 25 Therefore, in order to prevent leakage of air back through the coal as it is fed to the pulverizer feeder, it is necessary to provide a higher column of coal in the feed pipe to form a satisfactory seal.

Also during the recent years there has been 30 developed another method of firing coal under very large boilers which is known as the cyclone burner. This burner consists of a large water-cooled cylinder into which the coal is brought along with air under a fairly high pressure. 35 Because of the high pressure on the forced draft air, there is a very high air velocity developed as the air enters the cyclone burner. These conditions cause combustion to take place almost instantly with a very minimum of excess air, and therefore the efficiency of this method of combustion is excellent. However, the high pressure of the system necessitates the use of a still higher head of coal in the feed pipe to form a satisfactory seal.

40 If a standing column of coal is used as a seal, there also is a problem with the coal scales which are very often employed to weigh the coal as it is fed to the feeder. Inasmuch as these scales 45 are in the middle of a sealing column of coal, the scales themselves operate with an internal air pressure. Because of this internal air pressure, difficulty is experienced in making the scales pressure-tight, difficulty is experienced in servicing the coal scales, and also special provisions

need be employed in order to make the coal scales accurate.

It has been found in many plants that it is impossible to provide a sufficient column of coal ahead of the feeders in order to give satisfactory sealing on a space or headroom basis. It has also been found that feeding the coal against the pressure of the air is not as reliable as it should be because wet, fine, sticky coal tends to make a more perfect seal but the air pressure has a tendency to cause such coal to stop flowing entirely. Therefore, in order to insure more reliable coal flow and also in order to reduce the overall height of the boiler plant some other method of sealing against the air pressure is necessary.

One other such method is to use a star-type seal or feeder between the coal feeder and the cyclone burner. Such seals result in the coal being fed in a succession of small batches. Therefore combustion is not as satisfactory as it would be if the feed were more uniform. Furthermore the loss of air back through such a seal is greater than it should be and the maintenance of this type of equipment is quite high because of the rubbing of the star-shaped core against the housing.

Another type of seal that has been employed is the screw feeder which is run full of coal at all times and which has a short pitch at its discharge end. It has been found difficult to force the coal into the screw at the feed end partly due to the air pressure differential that exists across the screw and partly due to the relatively small size of the screw in relation to the other equipment.

In the operation of boiler plants with pressure furnaces, there also exists a danger, that the coal may hang up in the bunker and not flow out through the outlet provided therefor. Under these conditions, if the operator stops the flow of feed air to the burner, the hot furnace gases will vent back through the system to the bunker. Inasmuch as the temperature within the furnace is several thousand degrees, it is obvious that damage will result to the various pieces of equipment between the bunker and the furnace, and also the coal that does remain in the bunker will catch on fire. This can happen almost instantly. Such a condition is very dangerous to operators and also it may result in the complete stoppage of steam generation and in the case of a public utility may shut down the entire plant. For safety of operation of pressure furnaces, it is necessary that the system at some point ahead of the furnace be completely shut off at all times.

Accordingly, this invention provides apparatus in the nature of a bulk material scale for alleviating the undesirable features in pressure or vacuum systems as above described. More particularly, this invention provides a coal scale apparatus for eliminating the danger of fires and overcoming other disadvantages of coal feeding systems operated with pressure furnaces or burners.

This is accomplished by this invention with reference to coal handling by providing a coal scale apparatus wherein a pair of gas valves are arranged to effect a gas lock to prevent gases under pressure from traveling back through or into the system. At all times, at least one of the gas valves is maintained closed to stop any gases under pressure from moving beyond the apparatus. Further, a vent to any desired location can be provided in the apparatus to reduce the pressure of the gases trapped in the lock to substantially atmospheric pressure. In order to permit the gas valves to operate quickly and efficiently

without interference from the coal being transported through the apparatus, portions of the apparatus are arranged to constitute bulk material valves to keep any of the coal from being physically deposited on the gas valves. The two sets of valves cooperate in a correlated manner to accomplish the necessary function.

It is, therefore, an object of this invention to provide a bulk material scale apparatus of the nature indicated which will prevent gases under pressure from escaping at undesired points, or, in the event of a vacuum system, will prevent air entering the system at the point from which the bulk material is fed.

It is a further object of this invention to provide a coal scale apparatus for use in installation systems as previously described that will eliminate the danger of fires and that will overcome other disadvantages of present systems.

It is a still further object of this invention to provide a coal scale apparatus that will operate more efficiently and economically than any such apparatus presently available.

Other and further objects of the present invention will become readily apparent from a detailed consideration of the following description when taken in conjunction with the drawings in which:

Figure 1 is a view in side elevation partly broken away showing the coal scale apparatus of the present invention;

Figure 2 is a view in vertical section of Figure 1 taken along line 2-2;

Figure 3 is a view in vertical section of Figure 1 taken along line 3-3;

Figure 4 is a view in vertical section of Figure 2 taken along line 4-4;

Figure 5 is a view in horizontal section of Figure 4 taken along line 5-5;

Figure 6 is a view in vertical section of Figure 5 taken along line 6-6;

Figure 7 is a view in vertical section of Figure 5 taken along line 7-7; and

Figure 8 is a view in side elevation partly broken away showing a modified form for operation of the gas valves.

Referring now to the drawings, Figures 1-7 inclusive illustrate the new and improved coal scale apparatus. A main housing 10 encloses an endless conveyor belt 12 carried on pulleys 14 which are mounted on shafts 16 which are bearing supported in side plates 26. A weigh hopper 18 is suspended from one end of a weigh lever mechanism to be described hereinafter. Auxiliary housings 28, 21 and 22 are arranged on the main housing 10 to encase and protect portions of apparatus located outside the main housing 10. Further, an electrical compartment 24 is mounted on the main housing 10 for location of the necessary electrical equipment for operation of the apparatus. Each of the housings and the compartment are provided with doors to permit access thereto.

Within the main housing 10, the endless conveyor belt 12 is mounted on pulleys 14 as above described. Side plates 26 are mounted between shafts 16 to securely maintain the relative positions of the pulleys 14. Small rollers 28 support the conveyor frame and allow the entire feeder assembly to be removed for belt replacement. The upper part of the conveyor belt is supported by a flat plate 30. Directly above the belt 12 at this point is an opening 32 in the main housing 10. Skirt plates 34 are vertically mounted on either side of belt 12 between the opening 32 and

5

the conveyor. Also an end plate 33 is transversely positioned across the belt 12 at one end thereof.

The apparatus is normally joined to a source of coal such as a bunker by connecting opening 32 to the bunker outlet directly or through intermediate apparatus such as a coal valve, chute or downspout or any combination thereof. Hence, coal is fed to the belt 12 through opening 32 and is transported to the right of the conveyor, as shown in Figure 4, to be dumped. A scraping bar 35 is mounted with the conveyor just beyond the dumping point to keep coal from sticking on the belt 12 during its return run. However, practical experience indicates that some coal, particularly fine, evades the operation of scraping bar 35 and consequently a compartment 36 is provided for the collection of this coal.

The coal being dumped from the conveyor belt 12 passes through an opening 38 in a plate 40 and is received in the weigh hopper 18. Two pins 42 project from opposite sides of weigh hopper 18. The pins 42 are given rigidity by a conventional strut arrangement 44. A loop 46 attached to one end of a shaft 48 is secured to each pin 42. The other ends of the shafts 48 project through partitions 50 which constitute one wall of each of compartments 52 and are each joined to a scale bearing loop 54. The shafts 48 at their points of projection through partitions 50 are encased in molded rubber bellows 51 so that the compartments 52 are maintained pressure tight with respect to the space occupied by the weigh hopper 18. The compartments 52 communicate with the auxiliary housing 21. The scale bearing loops 54 cooperate with pivot pins 56 rigidly fastened to weigh levers 58 to provide a knife-edge attachment for the weigh hopper 18 with one end of the weigh levers 58. Each of the weigh levers 58 in compartments 52 is provided with a knife-edge pivot or fulcrum (not shown) by means of scale-bearing loops and pins. The other ends of the weigh levers 58 are interconnected by a bar 60 so they will operate as a single unit. Scale-bearing loops 62 cooperate with pins 64 rigidly fastened to weigh levers 58 to form a knife-edge attachment for a counterweight 66 with the other ends of weigh levers 58. The counterweight 66 is suspended between the scale-bearing loops 62.

The weigh hopper 18 is provided with a closure member 68 pivoted as indicated at 70 and has mounted therewith a counterweight assembly 72 which tends to keep closure member 68 shut. A solenoid housed in compartment 74 mounted on the weigh hopper 18 operates responsive to an electrical circuit to hold the closure member 68 against opening during the weighing cycle. After the desired weight is in hopper 18, the electrical circuit controlling the solenoid opens, thus allowing the closure member 68 to swing open and discharge the coal from the hopper 18. Coal being dumped from the hopper 18 passes out of the apparatus through outlet 75 to a downspout, chute, or pulverizer feeder or the like.

An electric motor 76 supplied from a suitable source is mounted on top of auxiliary housing 20. The motor output shaft 78 passes into auxiliary housing 21 where it is connected to a gear reducer 80. The output shaft 82 of the gear reducer 80 passes into main housing 10 and has a gear 84 mounted on its end. A gear 86 mounted on shaft 16 of the forward pulley 14 of the conveyor meshes with gear 84. Accordingly, the motor 76 is mechanically connected to the forward pulley 14 of the conveyor and thereby power is supplied to drive the conveyor belt 12.

6

The space occupied by the weigh hopper 18 is completely enclosed by the plate 40 fixed to the main housing 10 above hopper 18 as indicated at 90, a plate 92 fixed to the main housing 10 below hopper 18 as indicated at 94, a series of partitions extending between the plates 40 and 92 generally indicated as 96 and part of the main housing 10. As noted previously, plate 40 is provided with an opening 38. Joined by bolts 98 to plate 40 bounding opening 38 are steel bars 100 each provided with a Stellite edge 102 mounted thereon. Similarly plate 92 has an opening 104. Joined by bolts 106 to plate 92 bounding opening 104 are steel bars 108 each provided with a Stellite edge 110 mounted thereon. Series of rollers 112 and 113 each biased by a spring 114 or 115 respectively are mounted on opposite sides of each of the openings 38 and 104 respectively. Each of the rollers 112 and 113 is mounted on a diagonal element 116 and 117 respectively, pivotally supported on an elongated member 118 and 119 respectively so that they are individually urged toward their respective opening by the spring bias. This precise structure will be considered in greater detail with specific reference to Figures 5-7 inclusive. Plates 120 and 121 preferably of stainless steel are carried on each series of rollers 112 and 113 respectively.

A motor 126 mounted in auxiliary housing 20 is supplied from a suitable source of energy. The output shaft 128 of motor 126 drives a gear reducer 130 preferably of the worm gear type. The output or low speed shaft 132 of reducer 130 has mounted thereon a crank 134. A link 136 has one end pivotally attached to the crank 134 and the other end pivotally attached to crank 137, the other end of which is rigidly fixed to a shaft 138 which projects into main housing 10. This shaft 138 is mounted in bearings 140 and within main housing 10 has mounted thereon a pair of levers 142. The other ends of levers 142 are pivotally connected to one end of operating shafts 144. The other ends of operating shafts 144 are pivotally joined to one side of plate 121. Hence operation of motor 126 will cause levers 142 to oscillate and thereby effect movement of the plate 121 on rollers 113. Mounted in conjunction with link 136 and crank 137 are limit switches 146 and 147 to control the operation of motor 126.

A motor 150 supplied from a suitable source of energy is mounted in auxiliary housing 22. The output shaft 152 of the motor 150 is coupled to the input shaft of a gear reducer 154 preferably of the worm gear type. The low-speed shaft 156 of reducer 154 has fixed thereon a crank 157. To the end of crank 157 is pivotally connected a link 158. A crank 160 has one end pivotally attached to link 158 and the other end rigidly fixed to a shaft 162 which projects into main housing 10. This shaft 162 is mounted in bearings 164 and within main housing 10 has mounted thereon a pair of levers 166 and 167. The other ends of levers 166 and 167 are pivotally connected to one end of operating shafts 168 and 169 respectively. The other ends of operating shafts 168 and 169 are pivotally joined to one side of plate 120. Therefore operation of motor 150 will cause levers 166 and 167 to oscillate and thereby effect movement of plate 120 on rollers 112. Mounted in conjunction with crank 160 are limit switches 170 and 171 to control the operation of motor 150.

The structure immediately surrounding opening 38 is shown in detail in Figures 5-7 inclusive. The elongated members 118 are plates which are

fastened to the main housing 10 and plate 40, as by welding, on opposite sides of opening 38 as indicated in Figure 2. To each of these members 118 is joined an elongated block 180, as by welding, as indicated in Figure 7. At spaced intervals pivot pins 182 are located extending through member 118 and block 180. Each pin 182 is provided with bearings 184 and 186 adjacent either end. The member 118 is recessed to receive the head 188 of each pin 182 to prevent axial movement of the pin into and through the member 118 and block 180. Each pin 182 projects beyond block 180 and has fixedly mounted on the end thereof the diagonal element 116. To one end of each diagonal element is connected a 15 roller 112 by means of a short shaft 190 and suitable bearings (not shown) to permit the roller 112 to rotate freely. The other end of each diagonal element 116 is biased by a spring 114 positioned between this end of element 116 and plate 40. To assist the performance of spring 114, the plate 40 is recessed as indicated at 192, see Figure 7, to secure the relative position of spring 114. As noted previously, bars 100 are connected to plate 40 bounding opening 38 and each bar 100 is provided with a Stellite edge 102 mounted thereon. Plate 120 rides on rollers 112 and has guide strips 194 joined to its under surface to maintain the relative position of the plate 120 on the rollers 112. Hence it can be seen that 20 bars 100 and edges 102 constitute a valve seat and that plate 120 constitutes a gate valve head. The springs 114 tend to pivot their respective diagonal elements 116 about the axis of their respective pins 182 and move the rollers 112 upwardly thereby maintaining a gas-tight contact between the plate 120 and bar 100 and edges 102. In order to prevent injury or damage to this valve structure, the roller assembly is laterally offset 25 from opening 38.

Each roller 112 is independently lubricated. A grease fitting 196 is connected to the shaft 190 mounted in each diagonal element 116. The shaft 190 is hollow and communicates with the bearings for the roller 112. A flexible tube 193 is connected between each grease fitting 196 and a fitting 200 positioned in member 118. The fittings 200 are in communication with a manifold 202 (see Figure 4) which is supplied through a flexible tubing 204 communicating with the exterior of main housing 10 by means of fittings 206.

The members 118 have joined to one end thereof blocks 208 provided with threaded bores 210 to permit the roller 112 and plate 120 assembly to be connected to the main housing 10 by means of bolts 212.

While this assembly has been described as constituting the valve immediately above the weigh hopper 18, it is to be understood that this structure is substantially similar in all respects to the rollers 113 and plate 121 assembly immediately below the hopper 18, and surrounding opening 194.

The operation of the apparatus is as follows: Coal is introduced onto conveyor belt 12 through opening or inlet 32 from a bunker either directly or indirectly and is carried to the end of belt 12 where it is dumped through opening 38 into hopper 18 where it is weighed. Subsequent thereto, 70 it is dumped from the hopper 18 and passes through opening 184 and outlet 75 to a down-spout or the like and is eventually introduced into a zone of different gas pressure such as exists in a pressure furnace or a pressure burner such 75

as a cyclone-type burner. The operation is carried out in continuous batch fashion and consequently, the conveyor ceases to operate during the discharging cycle from the weigh hopper. The apparatus is generally divided into zones 5 as regards pressure. The space occupied by the conveyor as well as all apparatus preceding in the system is maintained continually at atmospheric pressure. The apparatus succeeding outlet 75 is continually under pressure. The space occupied by the weigh hopper 18 is a depressurizing zone and is alternately subjected to the pressure existing in the system and to atmospheric pressure.

The rollers 112 and plate 120 assembly constitutes a gate valve to prevent flow of gas through the system. Similarly the rollers 113 and plate 121 assembly constitutes a gate valve. For purposes of clarity hereinafter, the rollers 112 and plate 120 assembly will be referred to as the top gas valve and the rollers 113 and plate 121 assembly will be referred to as the bottom gas valve. An important concept of the present invention is that both gas valves are never open at the same time during normal operation.

In order to protect the gas valves and maintain them pressure tight at all times, coal is never deposited or dumped directly on either of plates 120 or 121. A bulk material valve is provided ahead of each of the gas valves in the system to operate before the gas valve in time to stop the flow of coal before the gas valve is closed. Also the gas valve is opened before the bulk material valve permits a resumption of coal flow.

The conveyor belt 12 constitutes the top bulk material valve and its operation is correlated with the top gas valve. The closure 68 of hopper 18 constitutes the bottom bulk material valve and likewise its operation is correlated with the bottom gas valve.

Accordingly, the several valves cooperate in a cyclic manner so that both gas valves are never open at the same time. This is accomplished by means of limit switches 143, 147, 170 and 171, the solenoid housed in compartment 74, a suitable electrical circuit to control the operation of motors 76, 126 and 150, the solenoid in compartment 74 and a limit switch on the weigh hopper levers, and another limit switch in compartment 74. This last limit switch is closed when gate 68 is closed. Operation of the weighing electrical control is the same as that described in my Patent No. 2,372,746 and as used in commercial coal scales of modern manufacture. The cycle of operation is as follows:

Consider as a starting point that the top gas valve is open, the bottom gas valve closed, the hopper 18 is empty, and the conveyor is stopped. 60 Since hopper gate 68 is closed, the limit switch in housing 74 is also closed, hence the electrical control circuit energizes the motor 76 and conveyor belt 12 begins its motion and dumps coal through opening 38 and into the hopper 18. When hopper 18 receives a predetermined weight of coal, the limit switch actuated by the weigh levers opens the motor 76 control circuit thus stopping motor 76, thereby stopping the motion of the conveyor belt 12. The motor 150 is energized to close the top gas valve. Thereafter, motor 126 is energized and causes the bottom gas valve to open. The solenoid is de-energized, permitting the weight of the coal in hopper 18 to swing closure 68 open against counterweight 72. The coal then passes out of hopper 18 and

through opening 104 and outlet 75. When all the coal has left the hopper 18, the counterweight 12 will swing closure 68 shut. Thereafter, the solenoid is energized to hold closure 68 shut and motor 126 is energized to close the bottom gas valve. The motor 150 opens the top gas valve. The cycle is then completed and the apparatus is in the condition as described in conjunction with the starting point.

The gas under pressure which is admitted to the depressurizing zone when the bottom gas valve is opened is quickly dissipated when the top gas valve is opened which incidentally occurs before the weighing operation. Hence, the weighing operation takes place at substantially atmospheric pressure thereby eliminating weighing errors which otherwise might be introduced should the weigh hopper 18 and the scale lever mechanism be subjected to substantially different pressures.

An alternative manner for operation of the gas valves is shown in Figure 8. Here, a link 308 is connected between one end of the top gas valve 302 and a crank 304 mounted on shaft 305. Also mounted on shaft 305 is a gear 306 which has gear teeth 308 over approximately one-fourth of its periphery. Also, the gear 306 is provided with a radial extending slot 310. The gear 306 meshes with a similar gear 312 mounted on a shaft 313. A link 314 is connected between one end of the bottom gas valve 316 and a crank 318 mounted on shaft 319. Also mounted on shaft 319 is a gear 320 similar to gear 306. This gear 320 also meshes with a gear 322 in like manner to gears 306 and 312. Gear 322 is mounted on shaft 323. Gear 306 does not mesh with gear 320 nor does gear 312 mesh with gear 322 as pairs of gears 306—312 and 320—322 are laterally offset. A motor 324 supplied from a suitable source of power drives a gear reducer 326. The low speed shaft 328 of reducer 326 has mounted at the end a worm 330. Meshing with the worm 330 is a worm gear 332 carried by a bearing mounted shaft 334. Fastened on shaft 334 is a crank 336 with a pin 338 projecting transversely at the end thereof. Accordingly, operation of the motor 324 will cause crank 336 to rotate in a clockwise direction. As shown in Figure 8, the movement of crank 336 will result in pin 338 being received in radial slot 310 and moving gear 306 in a counterclockwise direction for about 90° thereby moving crank 304 to the position indicated as 340 and in opening the top gas valve 302. Movement of gear 306 results in a clockwise movement of gear 312 to the same angular degree. Hence, the radial slots will align and the pin 338 will pass into the radial slot in gear 312 and move this gear counterclockwise for about 90° returning it to its original position. Also the gear 306 will be moved clockwise the same degree thereby closing the top gas valve 302. As the radial slots in gears 312 and 322 now align, the pin 338 will pass into the radial slot in gear 322 and rotate this gear counterclockwise for about 90°. This movement causes gear 320 to rotate clockwise the same angular degree and results in opening the bottom gas valve 316 and moving crank 318 to the position indicated as 342. The radial slots in gears 320 and 322 now align and this permits the pin 338 to be received in the radial slot in gear 320 and rotate this gear about 90° in a counterclockwise direction thereby closing the bottom gas valve 316 and returning gear 322 to its original position. The crank 336 and pin 338 have now traveled through 75

360° and the gears and valves are again in their original positions. It therefore is apparent that the desired movements of both gas valves can emanate from the single motor 324. Therefore, when subjected to the electrical controlling circuit, the operation of motor 324 can be controlled in harmony with the cycle of operation, as previously described, to effectuate the desired result.

Since pin 338 enters the various slots travelling parallel to the sides of the slots, there is no hammer blow between the various parts. As a result, the mechanism can be run very fast without undue wear of parts or noise.

While this invention has been described in conjunction with specific embodiments, nevertheless, various changes or modifications obvious to one skilled in the art are within the spirit, scope and contemplation of the present invention as claimed.

20 I claim:

1. A system for feeding material to a zone having a pressure different from atmospheric that comprises a gastight compartment having an inlet and an outlet, a weighing device in said compartment, said weighing device having a closure element to permit discharge of material, a normally opened first valve positioned in said inlet, a normally closed second valve positioned in said outlet spaced from the closure element of said weighing device, means responsive to the reception in said weighing device of a predetermined amount of material to successively close said first valve and open said second valve, and means responsive to the discharge of material from said weighing device to successively close said second valve and open said first valve.

2. A system for feeding aggregate material to a zone having a pressure different from atmospheric that comprises a conveyor, an airtight compartment, a weighing device in said compartment, a normally open first valve establishing communication between said conveyor and said compartment, a normally closed second valve establishing communication between said compartment and said zone, means responsive to the reception in said weighing device of a predetermined amount of material to successively stop said feeding means, close said first valve and open said second valve, and means responsive to the discharge of material from said weighing device to successively close said second valve, open said first valve and start said feeding means.

3. A bulk material scale apparatus that comprises a housing divided into a feeding compartment with an inlet therefor and a gastight weighing compartment with an outlet therefor, a weighing device in said gastight weighing device having a closure element to permit discharge of material, top valve means positioned between said compartments to cut off the flow of gas therebetween, bottom valve means positioned below the closure element of said weighing device and in said outlet to cut off the flow of gas therethrough and controlling means connected to said valve means and correlating their movements to maintain at least one of said valve means closed at all times.

4. A system for feeding material to a zone having a pressure different from atmospheric that comprises a housing defining therein an inlet and an outlet, material storing means at atmospheric pressure connected to said inlet, said outlet connected to said zone, said housing divided into an atmospheric zone and a depressurizing zone, feeding means positioned in said atmospheric

zone to receive material from said storing means, a hopper in said depressurizing zone to receive material from said feeding means, scale means cooperating with said hopper to weigh the material therein, closure means on said hopper to permit the material to be discharged through said outlet into said zone, a top valve establishing communication between said atmospheric zone and said depressurizing zone, a bottom valve establishing communication through said outlet, and controlling means to operate the apparatus in continuous-batch fashion so that one of said valves is maintained closed at all times.

5. A system as defined in claim 4 wherein said feeding means and said closure means constitute material valves and are correlated by said controlling means to prevent the deposition of material on said top and bottom valves.

6. A coal scale apparatus for use with a furnace or the like having a pressure other than atmospheric that comprises a housing divided into a feeding compartment with an inlet therefor and a gastight weighing compartment with an outlet therefor, said inlet being connected to a coal storing means, a feeding means in said feeding compartment to receive coal from said storing means and to discharge the coal into said weighing compartment through an opening between said compartments, a weigh hopper in said weighing compartment to receive coal from said feeding means, closure means on said weigh hopper to permit the coal to be discharged through said outlet to the furnace, a top valve in the opening between said compartments, a bottom valve in the outlet, and controlling means to maintain one of said valves closed at all times.

7. A coal scale apparatus as defined in claim 6 wherein said feeding means and said closure constitute coal valves and are correlated by said con-

trolling means to prevent deposition of coal on said top and bottom valves.

8. A coal scale apparatus for use with a furnace or the like having a pressure other than atmospheric that comprises a housing defining therein an inlet and an outlet, said inlet being connected to a coal storing means, said outlet being connected to coal receiving means communicating with the furnace, said housing divided into an atmospheric pressure zone and a depressurizing zone, feeding means positioned in said atmospheric pressure zone to receive coal from the coal storing means and to discharge the coal into the depressurizing zone, a hopper in said depressurizing zone to receive coal from said feeding means, scale means cooperating with said hopper to weigh the coal therein, closure means on said hopper to permit the coal to be discharged through said outlet, a top gas valve between said atmospheric pressure zone and depressurizing zone, a bottom gas valve in said outlet, and controlling means to maintain one of said gas valve means closed at all times.

9. A coal scale apparatus as defined in claim 8 wherein said feeding means and said closure constitute coal valves and are correlated by said controlling means to prevent deposition of coal on said gas valves.

ARTHUR J. STOCK.
